UNITED STATES PATENT OFFICE.

EVERETTE FOSTER, OF WESSON, MISSISSIPPI.

WRENCH.

1,027,830.

Specification of Letters Patent.

Patented May 28, 1912.

Application filed November 4, 1911. Serial No. 658,544.

To all whom it may concern:

Be it known that I, EVERETTE FOSTER, a citizen of the United States, residing at Wesson, in the county of Copiah and State 5 of Mississippi, have invented certain new and useful Improvements in Wrenches, of which the following is a specification, reference being had to the accompanying drawings.

10 This invention relates to tools and more particularly to that class of tools that are called wrenches and are used for the purpose of tightening nuts on bolts, etc.

The object of this invention is to provide 15 a wrench which can be readily adjusted to fit the various sizes of nuts on which it is desired to use the same.

A further object is to provide means for 20 securely fastening the parts of the wrench rigidly together so that they will firmly clamp the nut in question.

Other objects of this invention will become apparent as it is more fully set forth.

In the accompanying drawings which 25 illustrates by way of example an embodiment of this invention, Figure 1 represents a view in elevation of a wrench in open position, and embodying this invention. Fig. 2 represents a view in elevation of the wrench in 30 its closed position for holding a nut and with parts broken away to show the construction of the device.

Similar reference characters refer to similar parts throughout the drawings.

35 In the construction, 1 represents the shank of the wrench which is provided with a plurality of V-shaped teeth 2 in the front portion thereof, and with a handle 3 at its inner portion. A pair of plates 4 have each 40 one of their outer corners 5 projecting and rounded as is clearly shown in the drawings and provided with holes 6 therein for the purpose of receiving a rivet 7 or the like in order to hold an inner jaw 8 of the 45 wrench. The inner jaw 8 is provided with a hole 9 therein to permit the easy movement of a stem 10 attached to the outer jaw 11 of the wrench. A plurality of teeth 12 are provided on the inner portion of the 50 stem and arranged to closely engage with the teeth 2 of the shank, when said stem is closed against the shank 1.

Provided on the inner portion of the stem 55 10 is a journal member 13 arranged to permit the rotation of a catch 14 therein, the catch 14 being provided with enlarged heads

15 and 16 for the purpose of engaging with the outer sides of the stem and shank and in the manner clearly shown in Fig. 2. This catch is arranged to clamp said parts 60 together so that the wrench will be held securely on the nut which its jaws engage with.

17 are rivets or other suitable fastening means for holding plates 4 securely to the 65 shank 1. These plates are sufficiently separated to permit the easy movement of the stem 10 therein, and yet at the same time provide a guiding means therefor.

When it is desired to use the wrench, the 70 catch is undone and the inner portion of the stem drawn away from the shank and then pushed outwardly so that the jaws of the wrench will be separated sufficiently apart to properly engage with the nut or 75 the like to be actuated. It will be noticed that the inner jaw being pivoted will move out slightly so as to prevent any binding action of the same on the stem. The stem 10 is then moved inwardly so that its teeth 80 will engage with the teeth in the shank 1 and thereby prevent any longitudinal movement of the stem and thus prevent the jaws loosening off the nut. The heads 15 and 16 of the catch being then moved inwardly 85 to engage and lock the shank and the stem together will prevent any transverse movement of the same and further assist in holding the wrench securely on the nut.

The operation of the other parts of the 90 device being clearly apparent from the drawings, it is not deemed necessary to describe them further, and obviously while there is shown but one form of this invention in the drawings, it is not necessary to 95 limit this application for Letters Patent to that particular form, or in any other way otherwise than necessitated by the prior art, as many modifications in the construction thereof may be made without departing 100 from the principles thereof, or coming within the scope of the appended claim.

Having thus described this invention, what is claimed is:—

A wrench comprising in combination a 105 shank having its front portion provided with V-shaped teeth thereon, a plurality of plates rigidly secured to the outer portion of said shank, each of said plates having an outer corner portion projecting outwardly therefrom and provided with a hole 110 therein, an inner jaw having an end por-

tion disposed in said projecting portions, means for pivotally holding said jaw to said projecting portions, said jaw being provided with a hole therein, an outer jaw, a 5 stem, integrally secured to said outer jaw and provided with a plurality of V-shaped teeth thereon arranged to engage with the teeth of said shank, said stem being arranged to actuate within the hole in said 10 inner jaw and means rotatably held on said

stem for locking said stem and shank together, so that the teeth thereof will be held into engagement with each other.

In testimony whereof I hereunto affix my signature in the presence of two witnesses. 15

EVERETTE FOSTER.
